UNITED STATES PATENT OFFICE.

JOHANN BURIC, OF CRANFORD, NEW JERSEY, ASSIGNOR OF ONE-HALF TO HENRY J. MEWES, OF NEW YORK, N. Y.

TABLE.

1,273,730.

Specification of Letters Patent.

Patented July 23, 1918.

Application filed January 17, 1918. Serial No. 212,248.

To all whom it may concern:

Be it known that I, JOHANN BURIC, a subject of the King of Austria, and a resident of Cranford, Normandie Park, in the county 5 of Union and State of New Jersey, have invented a new and Improved Table, of which the following is a full, clear, and exact description.

Among the principal objects which the 10 present invention has in view are: to provide means for adjusting a table of the character mentioned for service; to provide a simple means for housing or otherwise disposing of the extension members; and to 15 simplify and cheapen the construction of the table.

Drawings.

Figure 1 is a side elevation of a table 20 constructed and arranged in accordance with the present invention, the parts thereof being shown in their contracted relation;

Fig. 2 is a bottom view of the same;

Fig. 3 is a longitudinal section, one of the 25 extension members being completely withdrawn from its housing at one end of said table and the corresponding extension member at the opposite end of said table being partially withdrawn from its housing, the 30 section being taken as on the line 3—3 in Fig. 2;

Fig. 4 is a sectional view taken as on the same line in Fig. 2, the two inner extensions being shown as fully withdrawn from their 35 housings, and two outer extensions being shown as partially withdrawn from their housings;

Fig. 5 shows a longitudinal section of the 40 fully-extended table;

Fig. 6 is a vertical cross section of a central fragment of a table constructed in accordance with the present invention, the section being shown as on an enlarged scale and taken as on the line 6—6 in Fig. 1;

Fig. 7 is a detail view in vertical section, the section being taken as on the line 7—7 in Fig. 6;

Fig. 8 is a detail view on an enlarged scale 50 in section, showing the lock for holding the extension members of the table together.

Description.

As seen in the drawings, a non-extensible supporting frame for the table has legs 15 55 connected by side members 16, which sup-

port a cross brace 17 to which the adjacent ends of permanent table leaves 18 are directly attached. The brace 17 performs the double function of supporting the inner edges of the leaves 18 forming stops for the 60 superposed and operatively connected extension leaves 19 and 20.

The leaves 19 and 20, as shown best in Figs. 3 and 8 of the drawings, are operatively connected by means of a spring latch 65 21. When united by the latch 21, the leaves 19 and 20 are held in definite relation to a sliding frame 22 and a support 23. The support 23 is permanently attached to the inner end of the extension 19, a rest 24 being 70 formed on said support 23 for supporting the outer edge of one of the leaves 18 when the leaves 19 and 20 and the sliding frame supporting the same are drawn to the full extent and from under the leaves 18. 75

It will be seen best in Fig. 3 of the drawings and at the right hand side thereof, that when the leaves 19 and 20 are drawn completely from under the adjacent leaf 18, the latch 21 and the operating button 25 thereon are exposed.

The latch 21 is pivotally mounted by a pin 26 in a housing formed by a cover plate 27 at the inner end of each of the leaves 19. The button 25 on the latch 21 is held flush 85 with the upper surface of the leaf 19 by a stop 28. The stop 28 is normally held against the under side of the cover plate 27 by a spring 29, which spring serves to maintain the latch head 30 of the latch 21 in the 90 socket 31. When the head 30 is in the socket 31, the leaves 19 and 20 are held in operative relation.

When either pair of the leaves 19 or 20 has been drawn from under the adjacent 95 leaf 18, the button 25 may be depressed to lift the head 30 from the socket 31. In this position of the latch 21, the leaf 20 may be drawn from under the leaf 19. The sliding frame 32 being permanently attached to the leaf 20 and sliding in grooves provided therefor in the frame 22, the sliding members of the frame 32 are rigidly connected by the end panel 33 of the table. The sliding frame 32 provides abutments or rests 34 105 for supporting the outer edges of the leaves 19 when the leaves 20 are fully extended.

It will be understood that while both the leaves 18 and 19 are secured at their inner edges, the outer edges are free to lift, which 110

permits the passage of the leaves 19 and 20, respectively, in a plane subsequently occupied by said outer edges of said leaves 18 and 19.

- 5 As seen best in Fig. 5 of the drawings, the leaves 19 and 20 are partially supported in their fully extended condition by the swinging legs 35. The legs 35 are supported in framed relation by the cross braces 36 and 10 37, the latter of which is hinged to a cleat 38 secured permanently to the under side of the leaf 20. Normally, the legs 35 are disposed in the raised position shown in Fig. 4 of the drawings, by means of gravity latches 39, 15 which engage the brace 36 when the said legs are lifted to the folded position. When the legs 35 are lifted to their folded position, the leaves 20 and parts connected therewith are pushed back under the leaves 19, to accomplish which the outer or free edges of the leaves 19 are lifted to permit the inner edges of the leaves 20 to pass thereunder. The 20 guide grooves 40 in the frames 22 are inclined so that when the outer end of the leaves 20 pass below the outer ends of the leaves 19, the outer ends of the said leaves 19 are lowered to the operating level thereof. In this position, the leaves 20 are pressed back to the position assumed in Fig. 3 of the 25 drawings and shown best at the right hand side thereof. In the position just above described, the latch 21 engages the leaf 20 to hold the leaves 19 and 20 thereafter in operative relation.
- 30 35 As shown best in Fig. 6 of the drawings, the sliding frames 22 have dove-tailed or T-shaped grooves 41 wherein roll frame guides for the rollers 41. The rollers 41 are secured to each of the supports and at the 35 opposite ends thereof. These rollers are arranged in pairs and mutually engage the grooves 40 of the adjacent member of the frames 22. While the rollers 41 are herein shown as operatively engaging T-shaped 40 grooves 40, it will be understood that other forms of grooves and sliding members disposed therein may be employed in lieu of the rollers and grooves disclosed.

It will be understood that the leaves 18 45 and 19 are hinged or pivotally connected with their supporting frames at the inner edge thereof, sufficient movement being accorded to the outer edges of each of the mentioned leaves to permit the lift of the outer edges for the passage thereunder of the fixed edge of the adjacent leaf, as, for instance, the hinge 42, which holds the leaf 19 to its support at the inner end of the said leaf, permits the lift of the outer edge of the leaf

for the insertion thereunder of the inner edge of the adjacent leaf 20.

As seen best in Figs. 5 and 7 of the drawings, the central leaves 18 are flexibly connected, one of said leaves being provided for this purpose with a tongue 43.

As shown in Fig. 6 of the drawings, the tongue 43 extends across the width of the table and serves to hold the meeting edges of the said leaves 18 in mutual alinement. The inner edges of the leaves 18 are structurally secured to the cross brace 17 by screws 44. The movement of the leaves 18 are guided by the blocks 45, which are rigidly secured to said leaves adjacent the opposite side of the table, as shown in Fig. 6 of the drawings. The blocks 45 normally rest in openings 46 in the cross brace 17. When the leaves 18 rock on the joint formed on the tongue 43, the blocks 45 serve to maintain the alinement of said leaves with each other and with the brace 17.

Claims.

1. A table comprising a plurality of slidably connected extension frames; a plurality of leaves pivotally mounted, each on one of said frames, each of said leaves being adapted to be lifted at the outer edge thereof for the passage thereunder of the outwardly adjacent leaf; and means for locking said leaves together when in their retracted position, said means being operable only when exposed, said means embodying a series of manually operable latches, each mounted in one of said leaves to be covered by the inwardly adjacent leaf and to normally lock the outwardly adjacent leaf.

2. A table comprising a plurality of slidably connected extension frames; a plurality of leaves pivotally mounted, each on one of said frames, each of said leaves being adapted to be lifted at the outer edge thereof for the passage thereunder of the outwardly adjacent leaf; and means for locking said leaves together when in their retracted position, said means being operable only when exposed, said means embodying a plurality of spring latches, one mounted in each of said leaves to extend therethrough for engaging the outwardly adjacent leaf when in retracted position, said latches being exposed for operation only when withdrawn from under the inwardly adjacent leaf with which they are associated.

JOHANN BURIC.
